UNITED STATES PATENT OFFICE.

EUGENE HAYFORD, OF SPOKANE, WASHINGTON.

ROAD GRADER AND PACKER.

1,406,558.

Specification of Letters Patent. Patented Feb. 14, 1922.

Application filed September 7, 1920. Serial No. 408,590.

To all whom it may concern:

Be it known that I, EUGENE HAYFORD, a citizen of the United States, residing at Spokane, in the county of Spokane and State 5 of Washington, have invented new and useful Improvements in Road Graders and Packers, of which the following is a specification.

This invention relates to improvements 10 in road graders and packers for road making work.

It is one of the objects of this invention to provide a grader and packer composed of a plurality of sections which are not only 15 united with each other in a novel manner but which are also connected with an equalizing bar by means serving to prevent the sections from slewing.

A further object of the invention consists 20 in providing one of the sections with a packer and grader having a portion projecting laterally from such section and in connecting the next adjacent section in following relation with such projecting portion so 25 that an overlapping grading and scraping result will be afforded without any break in the continuity of the road surface.

A further object consists in providing a main section which is reversible, top to bottom, whereby the scraping irons of either 30 the upper or lower portion of the section may be brought into play in case the irons of one portion become warm. In connection with this reversible feature, the main section is provided with a platform which is 35 adapted to be altered in position in accordance with the adjustment or reversal of said main section so that in any adjustment of the latter, the platform will be in a lower 40 receiving position.

A further object of this invention is to provide the device with runners which are so connected with the scraper that in certain 45 adjustments, the scraper will be elevated by the runners out of contact with the road surface while in other adjustments the device will be lowered into contact with the road surface.

The invention has many other objects and 50 features which will be more fully described in connection with the accompanying drawings and which will be more particularly pointed out in and by the appended claims.

In the drawings,

55 Figure 1, is a plan view of the scraper and

packer with the scraper bar folded in place in the wing section.

Figure 2, is a sectional view on line 2—2 of Figure 1.

Figure 3, is a longitudinal vertical sec- 60 tional view on line 3—3 of Figure 2.

Figure 4, is a sectional view on line 4—4 of Figure 1.

Figure 5, is a plan view of the scraper with the scraper bar, projected into an ex- 65 tended position and in draft connection with the equalizing bar.

Like characters of reference designate 70 similar parts throughout the different figures of the drawings.

As illustrated, 1 designates the equalizing or draft bar, 2 the main scraper section, 3 the wing section and 4 the finisher scraping bar.

Reference will now be specifically made 75 to the main section.

Said main section has a front scraper and packer portion which is canted with respect to the line of draft and which is of substantially U-shape in cross section, the same 80 having an upright bite 5 and horizontally disposed limb 6, preferably of wood. The front face of the bite 5 is of sheet metal, as indicated at 7, and the scraping irons are angle irons which are designated at 8. Thus 85 the scraper portion has upper and lower angle irons or scraper irons either of which may be used dependent upon the position of the main section. It is a feature of this invention to provide a reversible main sec- 90 tion which can be turned bottom side up from the position shown should the lower angle iron or scraper iron become warm. This feature of the invention provides means for not only prolonging the life of the 95 structure but also making it possible to continue work without stopping for repairs.

Said main section has a rear packing portion 9, which is substantially at right angles to the line of draft and which may be composed of vertical timbers 10 and horizontal timbers 11. The lowermost timber 11 will function primarily as a packer in trailing relation to the front packer portion but will not be provided with protecting irons as in 100 the case of the front portion which functions both as a scraper and packer. As the section advances, the gravel and dirt will ride above the lower scraper iron 8, against the metallic facing 7, and will slew lengthwise 105 110

of the protecting irons toward the left of the line of draft. Therefore, the front packer portion is protected from the excessive wear to which it would otherwise be subjected.

- 5 The front and rear packer portions are united by a frame which consists of frame members 12, 13, 14 and 15. The opposite ends of these frame members are rigidly connected with the front and rear packer 10 portions, and by reference to Figure 3, it will be seen that the lower edge of said frame member 14 is slightly elevated with respect to the road surface thereby localizing the contact wear upon the bottoms of the 15 front and rear packer portions. By reference to Figure 2, it will be seen that the frame members 12 and 13 are spaced apart to form a runner-way 16, the members 14 and 15 being likewise spaced apart to form 20 a runner-way 17. As both runner-ways, and the runners therein, are identical in structure and operation, only one need be described in detail.

With reference to Figure 3, 18 designates 25 a runner which is of sufficient length so that its rear end 19 may bear against the front face of the rear packer portion in such a manner that the drag imposed upon the runner, when the latter is in an operative ad- 30 justment will be prevented from straining the connecting means between the runner and the frame, the rear end of the runner impinging against the rear packer portion. The runner 18 has an upwardly curved por- 35 tion 20 which may be surfaced with metal 21, the metallic strip 21 extending rear-wardly along the upper face of the runner, as indicated at 22. A cylindrical element 23 is interposed between the members 14 and 15 40 and abreast of the upper face of the runner. A pin 24 is journaled in the members 14 and 15 and extends through the element 23 eccentrically to the longitudinal center there- 45 of. Straps 25 extend about the element 23 and have their terminal ends 26 fixed on to the sides of the runner 18, there being two straps for each runner. A lever 27, fixed to the element 23, may be employed to turn said element 23 into a runner elevating position, 50 as shown in Figure 3, or to the right of such position to depress the runner into an operative position and elevate the section with respect to the road bed or surface. This per- 55 mits of readily dragging the main section across a railroad track or bridge without re- sulting damage from the scraper irons. The metallic facing 22 comes into effective play when the element 23 is adjusted to elevate the scraper section and depress the runner. 60 It will now be clear how inevitable lost mo- 65 tion will permit the drag on the runner to force the latter rearwardly so that the im- pinging end 19 will relieve the straps 25 of what would otherwise be damaging drag strain.

I will next describe a novel platform construction whereby the platform may be re-versed upon reversal of the main section.

Holding portions 28 and 29 are mounted upon frame member 13 and holding portions 70 30 and 31, are mounted upon frame member 14. These members or boards constitute upper and lower sets of inwardly projecting flanges. A set of platform boards 32, rests upon the lower flanges 28 and 30. A wedge 75 33 or locking bar is interposed between the upper set of flanges 29 and 31 and the platform boards 32 to effectively hold the latter down against the flanges 28 and 30. The bar 33 may be secured in any desired manner 80 by spikes 34. However, the important fea- ture is that when the main section is re-versed, bottom side up, from the position shown, the platform boards 32 will be sup- 85 ported on the flanges 29 and 31, and the bar 33 will be interposed between the platform boards and the flanges 28 and 30. Thus in either adjustment, the platform will be in a proper receiving position either for support- 90 ing an operator or for receiving rock or other weight material.

Reference will next be made to the im- 95 proved wing section 3, which has a for-wardly disposed packer and scraper portion 35 which is parallel with the canted portion 95 on the main section. The canted portion on the main section projects laterally thereof, as indicated at 36, and the inner end of the wing section extends behind this projecting portion so that the resulting overlap will 100 avoid any break in the continuity of the finish of the road surface. The packer portion 35 may consist of a forward member 37 hav- 105 ing angle irons 38. The rear portion 39 is suitably secured in spaced relation to the forward member 37. A platform, comprising a plurality of boards 40 is secured mid-way of the height of the wing scraper section and their rear ends are united by timbers 41.

By means of this central disposition of the 110 wing platform, this wing section may be re-versed without altering the relative position of the platform thereof with respect to the height thereto. It may also be stated that the pins 24 are disposed centrally between 115 the upper and lower edges of the frame members so that when the main section is adjusted bottom side up, the runners may likewise be reversed, the eccentric elevating and depressing mechanism working inter- 120 changeably irrespective of the position of the main section. The wing section is shown hingedly connected with the main section by means of hinged links 42 so that the wing section may be tilted upwardly and then 125 onto the main section, when desirable or ad- vantageous. In order to take the strain off from the hinges 42, the wing section is connected with the main section by means of a draft connection 43.

In cases where it is desirable to extend the reach of the scraper, especially where the scraper has been advanced over the road bed more than once and where it is desired to 5 provide a finished surface and distribute all of the dirt slewed off from the wing scraper, then, a finishing bar is employed which I will now describe in detail.

This finishing bar or section is designated 10 at 44 and is pivoted between the members 37 and 39 at 45. The remaining end 46 of said bar may be suitably supported, as at 47, when in a retracted or folded position as shown in Figure 1. In Figure 5, the scraper section is 15 extended.

It is a novel feature of this invention to provide not only a draft connection between an equalizing bar and the several sections of the scraper, but it is also a feature to provide 20 such draft connection in such a manner that the imposed drag load will function to prevent slewing movement of the main or heavier section of the scraper. It is also a feature of this invention to provide a relatively 25 heavy equalizing or draft bar so that the draft imposed on the sections will not exercise an elevating stress tending to lift the scraper sections off from the surface, but will on the contrary, exercise a downward 30 stress tending to hold the scraper sections in sustained engagement with the road surface. It is additionally a feature of this invention to connect the draft cables at a relatively 35 high elevation on the scraper sections to supplement the action of the equalizing bar in causing the draft pull to cause said sections to engage the road surface.

In Figure 3 I have shown one draft cable 48, connected with the upper part of the 40 scraper portion. The remaining end being connected with the equalizing bar 49 and such remaining end inclining downwardly from its connection with the main section because of the relatively heavy equalizing bar, 45 in part, and in part by reason of the high connection of the cable with the scraper. The main draft connection is indicated at 50. A draft connection 51 is connected with the equalizing bar and with the wing section, 50 and if the scraper or finishing section is employed, a draft connection 52 is utilized. Now it will be seen that if no further draft 55 connections were employed, there would be a sagging backward of the adjacent ends of the wing and main sections. To counteract such defective action and to also prevent slewing of the main section I provide draft connections or cables 53 and 54 which are connected with the main section at 55 and 56 and with the bar 49 at 57. By reason of the draft connection 43, and for other advantageous reasons such as facilitating the 60 tilting of the wing section, the cables 53 and 54 are not required to be connected with the 65 wing section. It will be noted that these

anti-slewing cables 53 and 54 are not only disposed angularly to the line of draft, but it will also be noted that they exercise a pull on the main section in a direction angularly to that stress of the dirt which would otherwise act to slew the main section to the right of the line of draft. Thus I employ the usual and necessary draft cables in such a novel manner that they not only perform their functions as draft cables but they also 70 75 function as anti-slewing means.

It is believed that my invention will be clearly understood from the foregoing description, and while I have herein shown and described one specific form of my invention, 80 I do not wish to be limited thereto except for such limitations as the claims may import.

I claim:

1. In a road scraper and packer, a main 85 section having a front scraper and packer portion canted with respect to the line of draft and provided with top and bottom scraping irons for individual use upon reversal or over turning of said section, a 90 rear packer portion for said section, a frame connecting said front and rear portions, a platform, and means for securing said platform in a lower position with respect to said section irrespective of the side or face of said 95 section which is adjacent the road.

2. In a road scraper and packer, a main 100 section having a front scraper and packer portion canted with respect to the line of draft and provided with top and bottom scraping irons whereby said section may be reversibly used, a rear packer portion, a frame uniting said front and rear packer portions and having flanged platform holding members in super-posed relation, a platform adapted to rest on said holding portions, and wedge bars for insertion between the platform and certain of said holding portions whereby when said section is reversed in its working position the platform 105 110 may be disposed in a lower position with respect to the top of said section.

3. In a road scraper and packer, a main section having front and rear scraper portions and including a frame uniting said 115 portions, said frame having laterally disposed open runner ways, runners in said ways, and eccentric lever devices connecting said runners with the frame whereby the section may be elevated out of contact 120 with the road surface and disposing the load of said section onto said runners.

4. In a road scraper and packer, a main section having front and rear scraper portions and including a frame uniting said 125 portions, said frame having an open runner way, a runner disposed in said way, an eccentric rotatively and eccentrically journaled in said way and extending across the same and abreast of the top of the runner, hangers 130

- on said runner engaging the periphery of said eccentric to support said runner off from the road when not in use, and a lever mounted on said eccentric for turning the 5 same into bearing support onto said runner whereby the eccentric engagement with the frame will elevate said main section out of contact with the road surface.
5. In a road scraper and packer, a main 10 section having front and rear scraper portions and including a frame uniting said portions, and runner mechanism for said section having elevating and lowering means for raising said section off from or lowering 15 it onto the road surface, said runner mechanism having trailing engagement with said section to take the drag strain off from said means.
6. In a road scraper and packer, a main 20 section having a front scraper and packer portion canted with respect to the line of draft and projecting laterally on one side of said section, a wing section in draft connection with said main section and project- 25 ing or having a front packer portion canted with respect to the line of draft and in over lapping relation with the projecting portion of said main section.
7. In a road scraper and packer, a main 30 section having a front scraper and packer portion canted with respect to the line of draft and projecting laterally on one side of said section, a wing section in lateral relation with respect to said main section and 35 hingedly connected therewith to be tilted upwardly and onto said main section, said wing section having a canted packer por- tion with one end thereof projecting behind and in following relation to the projecting packer portion of said main section.
8. In a road scraper and packer, a main 40 packer section, a wing packer section connected with said main section, and a finisher bar or section carried by and adapted to be projected from said wing section.
9. In a road scraper and packer, a main 45 packer section, a wing packer section connected with said main section, and a finisher section extensively connected with said wing section.
10. In a road scraper and packer, a main 50 packer section, a wing packer section connected with said main section, a finisher section connected with said wing section, an equalizing bar, and means connecting said sections with said equalizing bar.
11. In a road scraper and packer, a main 55 packer section, a wing packer section laterally connected with said main section and in draft connected relation therewith, and equalizing means connected with both of 60 said sections.
12. In a road scraper and packer, a plu- 65 rality of packer sections, an equalizing bar, means connecting said bar with said sections and extending in the line of draft, and means connecting one of said sections with said bar and extending angularly to the line of draft for arresting slewing movement of said sections.

In testimony, that I claim the foregoing 70 as my own, I hereby affix my signature.

EUGENE HAYFORD.
